United States Patent Office

Des. 188,184
Patented June 14, 1960

188,184

CHAIR

William H. Sullivan, Shaker Heights, Ohio, assignor to The B. L. Marble Chair Company, Bedford, Ohio, a corporation of Ohio

Filed Oct. 5, 1959, Ser. No. 57,803

Term of patent 14 years

(Cl. D15—1)

Fig. 1.

Fig. 2.

Figure 1 is a perspective view illustrating the front and one side of a chair embodying my new design; and Figure 2 is a perspective view illustrating the rear and one side thereof.

I claim:

The ornamental design for a chair, as shown.
